US0D1107706S

(12) **United States Design Patent** (10) **Patent No.:** **US D1,107,706 S**
Kurihara (45) **Date of Patent:** **** Dec. 30, 2025**

(54) **ELECTRONIC DEVICE CONTROLLER HOUSING**

(71) Applicant: **SONY INTERACTIVE ENTERTAINMENT INC.**, Tokyo (JP)

(72) Inventor: **Daisuke Kurihara**, Chiba (JP)

(73) Assignee: **SONY INTERACTIVE ENTERTAINMENT INC.**, Tokyo (JP)

(**) Term: **15 Years**

(21) Appl. No.: **29/883,047**

(22) Filed: **Jan. 23, 2023**

(30) **Foreign Application Priority Data**

Aug. 5, 2022 (JP) ..... 2022-016803 D

(51) **LOC (15) Cl.** **21-01**

(52) **U.S. Cl.**

USPC **D21/333; D14/401**

(58) **Field of Classification Search**

(57) **CLAIM**

The ornamental design for an electronic device controller housing as shown and described.

DESCRIPTION

FIG. 1 is a perspective view of front, bottom and right side of an electronic device controller housing showing my new design;

FIG. 2 is a perspective view of rear, top and left side thereof; FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the electronic device controller housing that form no part of the claimed design.

1 Claim, 6 Drawing Sheets
